DIFFUSED DISCHARGE LAMP

Chester H. Braselton, New York, N. Y., assignor
to Sirian Lamp Company, Newark, N. J., a corporation of Delaware

Application October 9, 1930, Serial No. 487,395

7 Claims. (Cl. 176—1)

This invention relates to electric discharge devices and particularly to such devices in which a uniform discharge is desired.

One of the objects of the invention is to produce an electric discharge device in which the discharge is distributed uniformly over considerable area.

Another object of the invention is to increase the potential difference between adjacent parts 10 of the device so as to form an arc between them.

Other objects of the invention and objects relating to the construction and assembly of the various parts will be evident as the description of the invention proceeds.

15 One embodiment of the invention has been illustrated in the accompanying drawing in which:

Fig. 1 is a perspective view of my improved

lamp; and

Fig. 2 is an enlarged longitudinal sectional view 20 of a portion of the electron emitting element.

In my application entitled Electrical discharge device filed June 3, 1930, Serial No. 459,048, I describe a discharge device in which a coil of filamentary resistance wire is coated with an electron emitting material and when energized in an atmosphere of ionizable gas under suitable pressure a discharge takes place longitudinally of the coil which surrounds the coil like a halo producing an intense illumination. The present invention contemplates the use of such coils closely positioned in parallel relation and connected electrically in series in such a way that potential difference between adjacent points on any parts 25 of the coils is substantially the same. Such a device may be constructed in the following manner:

An envelope 10 of glass or any other desired transparent material may be sealed upon the usual press 11 for supporting the elements of the device. A pair of electron emitting elements 12 and 13 may be mounted at one end upon the support rods 14 and 15 which are sealed in the press 11 and at the other end upon the support rods 16 and 17 which are also sealed in the press. All 30 of the support rods may extend upwardly within the bulb and may be so positioned that the elements 12 and 13 will extend in parallel relation and close to one another. A short connector 18 may be welded to the two support rods 15 and 16 to electrically connect them together and a pair 35 of leading-in wires 19 and 20 may be connected respectively to the support rods 14 and 17.

The electron emitting elements 12 and 13 may each comprise a coil 21 (see Fig. 2) of resistance wire such as tungsten, molybdenum, tantalum,

or nichrome, which may have a relatively small diameter so as to be stiff enough to support itself and may be coated with electron emitting material 22 which may be any of the well-known materials used for that purpose such as the oxides of the alkali earth metals or mixtures of such oxides and the mixture may preferably contain a material having selective radiation such as the oxides of yttrium, cerium, and calcium to increase the radiation therefrom. The latter oxide 10 may be preferred because it is electron emitting at temperatures which are not impractical. The electron emitting material may be applied to the coil in any desired manner as by a brush and the outer surface of the coil may be coated, 15 as indicated, or each individual turn may be coated.

With the elements mounted upon the press 11 and the press sealed in the envelope 10, as indicated, the envelope may be connected to a vacuum pump in the usual manner and an oven placed over it to raise the temperature to between 350 to 400° C. or to as high a temperature as the glass will stand without softening. The filament current is simultaneously turned on and the 20 temperature of the filament raised to about 600° C. or to a dull red heat. This drives out certain of the gases from the filament and other parts of the lamp and when there is no more gas present as is evidenced by the lack of fluorescence when high tension current is directed against the walls of the bulb and a high vacuum of preferably .5 micron is obtained current may be increased through the filament and the temperature thereof slowly raised until about 800° C. 25 30 35 is reached with a bright red color. This drives out the binder in the electron emitting material and other occluded gases that may be present. When no more gas is found in the bulb the oven may be raised and the filament heated to approximately 1200° C. the pump being connected all this time to maintain the high vacuum and draw the gases out of the bulb.

When the high vacuum is again obtained the pump may be shut off and the filament current 45 turned off and a slight amount of inert gas, such as neon, at about 1/2 mm. pressure may be admitted to the bulb and the filament current turned on again and gradually increased. Spots of localized discharge will then appear having a reddish color and will gradually spread until a diffused glow completely fills the bulb. This process appears to activate the electron emitting coating and may be maintained until the discharge is uniform throughout the entire bulb which 50 55

- usually takes less than ten minutes. During this time the current on the filament should not be raised too high so that the coating will not be destroyed or thrown off from the filament. If 5 white discharge spots appear on the filament or support rod it is an indication that there are more gases or vapors in the bulb and the bulb should preferably be again exhausted and the whole process of activation repeated.
- 10 When the activation is completed the filament temperature may be raised for a moment to about 1400° C. and the vacuum pump may again be connected and the gas pumped out to remove any undesirable gases which may have been 15 thrown off during the activation process. When the high vacuum is again obtained the filament circuit may be disconnected, the pump turned off, and about 50 mm. of neon gas admitted to the bulb followed by about 150 mm. of argon.
- 20 If desired the bulb may then be sealed off and flashed with magnesium to clean up the gases within the bulb. Magnesium may be introduced into the bulb by placing a small amount in a container 23 which may be attached by means 25 of a connector 24 to one of the support rods, as the rod 14. When the container is heated by external bombardment the magnesium flashes.
- When the device is connected to a power circuit current enters the lead-in wire 19 and passes 30 up through the support rod 14, through the electron emitting element 12, the support rod 16, the connector 18, the support rod 15, the electron emitting element 13, the support rod 17, and passes out through the lead-in wire 20. This 35 energizes the electron emitting elements 12 and 13 and it will be noted that inasmuch as they are the same resistance each, any point on one will have a difference of potential from a corresponding point on the other of approximately half 40 the potential across the lead-in wires 19 and 20 and thus a uniform difference in potential exists throughout the length of the elements.
- When the coils are raised to the proper temperature there is apparently an electron emission 45 from the electron emitting coating which ionizes the gas in the immediate vicinity of the coils. The ionized region in the vicinity of each of the coils appears to provide a conducting path along the coil which supports the discharge 50 therealong. Inasmuch however as there is a difference in potential between adjacent points on the two coils there will also be a discharge across the gap between the coils and thus the illumination of the device is greatly increased.
- 55 While I have described the use of neon and argon gas within the bulb other inert gases may be used but I prefer the monatomic gases such as neon, argon, helium, krypton, and xenon and mixtures thereof and I may also mix a small 60 quantity of a metal vapor, such as the vapors of mercury, calcium, rubidium, or caesium, with the gas in the bulb to increase the conductivity thereof or to produce color effects. The metal vapors may be introduced into the bulb by placing a salt of the desired metal in the container 65 23 adjacent the magnesium and when the magnesium is flashed it will combine with the salt liberating the free metal which then condenses on the inner walls of the bulb to be evaporated again when the bulb is heated in use.
- 70 While certain specific pressures of the gas have been mentioned these may be varied as greater pressures tend to confine the discharge closer around the filament and lower pressures appear to permit it to increase in diameter.

While a certain specific type of an electron emitting element has been illustrated and described other such elements may be used. For instance, the coil, instead of having a solid coating on the outer surface thereof, may have the surface partially coated or each individual turn may be coated with the material, or the coil may be wound around a core of electron emitting material, or the filament wire itself may have the electron emitting material incorporated in it such as thoriated tungsten wire which may be made by treating tungstic acid and thorium nitrate, or other constructions may be used, the essential feature being that sufficient resistance is provided for the particular voltage and current desired and that electron emitting material is in contact with at least a portion of the conducting element.

Many modifications of the invention may be resorted to without departing from the spirit thereof, and I do not therefore desire to limit myself to what has been shown and described except as such limitations occur in the appended claims.

Having thus described my invention what I desire to claim is:

1. In an electric discharge device a pair of substantially parallel electron emitting elements with one end of one element electrically connected to the opposite end of the other element, means to connect the other ends of both elements to opposite sides of a source of potential, and an inert ionizable gas surrounding said elements and having such a pressure that the ionization thereof is confined to the region of said elements when said elements are energized whereby in operation a uniform overlapping of the discharge from the two elements occurs, the breakdown potential of said gas per unit length along the element being less when energized by ionization from said element than the potential drop along the conductor necessary to raise the same to electron emitting temperature, and said electron emitting elements having an emissivity when heated in excess of that from thorium oxide.

2. In an electric discharge device a pair of substantially parallel, spaced apart, electron emitting elements with one end of one element connected electrically to the opposite end of the other element, means to connect the other ends of both elements to opposite sides of a source of potential, and an ionizable gas having a pressure in the neighborhood of 200 mm. of mercury surrounding said elements whereby in operation a uniform overlapping of the discharge from the two elements occurs, the breakdown potential of said gas per unit length along the element being less when energized by ionization from said element than the potential drop along the conductor necessary to raise the same to electron emitting temperature, and said electron emitting elements having an emissivity when heated in excess of that from thorium oxide.

3. In an electric discharge device a pair of substantially parallel, spaced apart, electron emitting elements with one end of one element electrically connected to the opposite end of the other element, means to connect the other ends of both elements to opposite sides of a source of potential, and a mixture of neon and argon gas surrounding said elements and having a pressure of substantially 200 mm. of mercury whereby in operation a uniform overlapping of the discharge from the two elements occurs, and said electron

emitting elements having an emissivity when heated in excess of that from thorium oxide.

4. In an electric discharge device a pair of substantially parallel, spaced apart, electron emitting elements with one end of one element electrically connected to the opposite end of the other element so that the elements are connected together in series, each of said elements comprising a filamentary resistance wire and electron emitting material in contact with said wire, and an ionizable gas surrounding said elements and having a pressure sufficient to confine the ionization thereof to the region of said elements when said elements are energized whereby in operation a uniform overlapping of the discharge from the two elements occurs, the breakdown potential of said gas per unit length along the element being less when energized by ionization from said element than the potential drop along the conductor necessary to raise the same to electron emitting temperature, and said electron emitting elements having an emissivity when heated in excess of that from thorium oxide.
5. In an electric discharge device a pair of conductors mounted on substantially parallel axes, spaced apart, with the end of one conductor connected electrically to the opposite end of the other conductor, means to connect the other ends of both conductors to opposite sides of a source of potential, electron emitting material in contact with one of said conductors, and an ionizable gas surrounding said conductors and having a pressure of substantially 200 mm. of mercury whereby in operation a uniform overlapping of the discharge from the two elements occurs, the breakdown potential of said gas per unit length along the element being less when energized by ionization from said element than the potential drop along the conductor necessary to raise the same

to electron emitting temperature, and said electron emitting elements having an emissivity when heated in excess of that from thorium oxide.

6. In an electric discharge device a coil of filamentary resistance wire, a second coil of filamentary resistance wire spaced from said first coil but substantially parallel therewith, means to connect one end of said first coil to the opposite end of said second coil, means to connect the other ends of both coils to opposite sides of a source of potential, electron emitting material in surface contact with one of said coils, and an ionizable gas having a pressure of substantially 200 mm. of mercury surrounding said coils whereby in operation a uniform overlapping of the discharge from the two elements occurs, the breakdown potential of said gas per unit length along the element being less when energized by ionization from said element than the potential drop along the conductor necessary to raise the same to electron emitting temperature, and said electron emitting elements having an emissivity when heated in excess of that from thorium oxide.

7. In an electric discharge device a pair of coils of filamentary wire spaced apart but substantially parallel with each other, a coating of electron emitting material on each of said coils, said coils having the end of one electrically connected to the opposite end of the other, means to connect the other ends of both coils to opposite sides of a source of potential, and a mixture of neon and argon gas surrounding said coils at a pressure of substantially 200 mm. of mercury whereby in operation a uniform overlapping of the discharge from the two elements occurs, and said electron emitting elements having an emissivity when heated in excess of that from thorium oxide.
